UNITED STATES PATENT OFFICE.

WINFIELD S. WILLIAMS, OF CHICAGO, ILLINOIS.

HINGE MECHANISM.

1,144,404.

Specification of Letters Patent. Patented June 29, 1915.

Application filed October 17, 1911. Serial No. 655,133.

To all whom it may concern:

Be it known that I, WINFIELD S. WILLIAMS, a citizen of the United States, residing at Chicago, in the county of Cook and State of Illinois, have invented a certain new and useful Improvement in Hinge Mechanism, of which the following is a full, clear, concise, and exact description, reference being had to the accompanying drawings, forming a part of this specification.

My invention relates to hinge mechanism and is of particular utility in connection with double acting doors although certain features of my invention are also otherwise applicable. The various features of my invention however will be readily understood in describing my invention as applied particularly to double acting doors. The description herein therefore concerns itself particularly with hinge mechanism for double acting doors and I will set forth in what follows a particular specific form which my invention may take.

The principal feature of my invention concerns itself with the provision of three hinge members, two of which are permanently mounted upon and associated with the third member in such a way as to be swung upon said third member and also adapted to inter-lock at certain angular positions. This feature of my invention may be applied to great advantage to hinge mechanism for double acting doors and in the particular form in which the invention is herein illustrated I have a hinge element mounted on the jamb and a hinge element mounted on the door; these hinge elements being united by a web adapted to cause the jaw of one element to interlock with the pivotal point of the other element at certain angles, and become the pivotal point on the release of the opposite element. The particular structure thus referred to contemplates a member having two pintles, one at each edge; and two hinge members pivotally attached thereto, each of said pivotally hung members provided on its opposite edge with jaws or clasps adapted to engage these pintles alternately as the door swings to and fro; the pintles being of such a character as to engage both jaws when the door is in its normal or closed position. Then as the door swings in one direction the jaws of one of the elements are disengaged from the pintles at one edge of the web, while the jaws of the edge of the other element are per-

manently interlocked and form a supporting element in the swinging of the door. The swinging of the door in the opposite direction reversing the process with the opposite pintle and jaws. Thus when my invention is applied to hinge mechanism for double acting doors I am able to dispense with one or more operating plates of the ordinary double acting hinge and I am also enabled at all time to provide a solid pivotal support for the door irrespective of the direction of its swing.

I will describe now the specific form outlined above which my invention may take in connection with the accompanying drawings, in which:

Figure 1 is a front view showing a hinge constructed in accordance with my invention; Fig. 2 is a sectional view on line *a—a* of Fig. 1, the hinge however being closed.

Referring more particularly to Fig. 1, I show a hinge element 14 which is adapted to be fastened to the jamb through the agency of suitable holding devices. This hinge element 14 has a pintle 3 held in place between lugs 5, 5. This hinge element having on one edge-jaws adapted to interlock with pintle 4. A second hinge element 13 is attached to pintle 4 with the lugs 5, 5, and has jaws 8, 8 on the opposite edge thereof adapted to interlock with the pintle 3. This hinge element 13 is adapted to be fastened to the door through the agency of suitable holding devices. The jaws of 8, 8, on hinge elements 13 and 14, being arranged for co-operation and interlocking under certain conditions with the pintles 3 and 4; the said jaws and the said lugs being adapted for association with and periodical interlocking with the pintles 3 and 4. The pintles 3 and 4 are cylindrical except that two flattened surfaces are provided as shown more clearly in Fig. 2.

A third hinge element 15 is in the nature of a central web member and is permanently associated with both pintles 3 and 4 so as to assist in transferring the weight of one pintle to the other. In this structure the member 13 is permanently associated with a pintle 4 and the member 14 is permanently associated with the pintle 3. Thus each member 13 and 14 carries a pintle and is adapted to engage at certain times the other pintles.

It will be seen that the opening 10 between the jaws 8 is of sufficient size to accommodate the flattened portion of the pintles 3 and 4 so

that should the pintles 3 and 4 pass through the opening 10 into the circular opening 11 and the opening 10 no longer be parallel to the flattened sides of this pintle, then the 5 jaws 8 hold the elements 13 and 14 in a rotatable position upon the pintles 3 and 4.

It will thus be seen that the element 13 swinging on the pintle 4 the opening 10 will be in proper position to slide past the flattened surface of the pintle 3 and if the pressure in that direction is continued the same interlocks with pintle 3 and the jaws 8 on hinge element 14 will pass free of the pintle 4. The pintle 3 becoming a pivotal point for 10 hinge element 13; the jaws on said 13 having passed away from parallelism with the flattened sides of the pintle 3. In a similar way 15 the element 14 may be swung about the pintle 4.

20 It will be noted that each of the hinge elements carries the pintle solidly held in one edge thereof and has jaws on the opposite edge thereof. And it will be noted that the central web member has means on the opposite edges thereof for the reception of said 25 pintles and rotation thereon. In this way a double acting hinge is provided which has but three plates. On account of the sides of the openings 10 and 12 being along the paths 30 of arcs described from the axes of the pintles 3 and 4, the elements 13 and 14 while

maintaining a pivotal relation to the web member 15 cannot be moved bodily away from the pintles as the openings 10 and 12 are not in exact coincidence when the door 35 is swung in either direction. There is no danger therefore of the door falling from the hinges. I do not mean to limit myself to such specific description and illustration, but

Having thus described one embodiment of 40 my invention, what I claim as new, and desire to secure by Letters Patent, is:

45 A double acting hinge having two interchangeable elements, either one of which may be the movable element and the other the stationary element, each element having a pintle and a pair of jaws provided respectively at opposite portions thereof, the jaws of one element being adapted to coöperate with the pintle of the other element, said 50 pintles and jaws having circular bearing surfaces, and a flat plate associated with the supporting portions of said elements to equalize the strain, said plate having a plurality of eyes by means of which it is pivotally associated with both pintles.

55 In witness whereof, I hereunto subscribe my name this 5th day of October, A. D. 1911.

WINFIELD S. WILLIAMS.
